(57) **CLAIM**

The ornamental design for an inflatable bed support system, as shown and described.

DESCRIPTION

FIG. 1 is a perspective view of the inflatable bed support system of the present design;

FIG. 2 is a front side elevation view of the inflatable bed support system of FIG. 1;

FIG. 3 is a right side elevation view of the inflatable bed support system of FIG. 1;

FIG. 4 is a left side elevation view of the inflatable bed support system of FIG. 1;

FIG. 5 is a top plan view of the inflatable bed support system of FIG. 1;

FIG. 6 is a bottom plan view of the inflatable bed support system of FIG. 1; and,

FIG. 7 is a back side elevation view of the inflatable bed support system of FIG. 1.

In the drawings, the broken lines showing the air pump, electrical cords and air hose form no part of the claimed design.
